2 Sheets-Sheet 2

UNITED STATES PATENT OFFICE.

WILLIAM M. SHEEHAN, OF ST. LOUIS, MISSOURI, ASSIGNOR TO COMMONWEALTH STEEL COMPANY, OF GRANITE CITY, ILLINOIS, A CORPORATION OF NEW JERSEY.

LOCOMOTIVE MUD RING.

Application filed December 16, 1926. Serial No. 155,323.

My invention relates to new and useful improvements in locomotives and more particularly to the foundation ring or mud ring which is a metallic member shaped to correspond to the ground plan of the locomotive fire box. It separates the inside and outside sheets of the fire box and forms the foundation to which these sheets are attached.

The present device is directed particularly to types similar to those locomotives in which the trailer trucks are arranged to take care of the pulling and buffing stresses. It has heretofore been customary to form the deck plate in a separate piece and bolt it to the rearward end of the mud ring.

My invention contemplates and its principal object is to form the deck plate and mud ring integrally.

Another object is to provide integral means for the attachment of the cab sheets.

A further object is to provide integral stoker supporting pads which may be located to accommodate different types of stokers by slight change in the core box arrangement at the time of casting.

A still further object is to provide the under-surface of a unitary mud ring and deck plate with integrally formed pads or brackets toward the rear end on the sides to rest on the roller or rocker members of the trailing truck.

With the foregoing and other objects in view my invention consists in certain features of construction and arrangement of parts hereinafter more fully described and illustrated in the accompanying drawings, in which—

Figure 1 is a top plan view of my integrally formed mud ring and deck plate.

Figure 2 is a side elevation showing the arrangement of the parts in relation to a locomotive.

Figure 3 is a plan view of a modified form providing for a different type of stoker and having a mud ring of different cross section.

Figure 4 is a side elevation of the modified form shown in Figure 3.

Figures 5 to 10 are cross sectional views showing various forms and modifications of mud rings and the method of attaching the inner and outer fire box sheets thereto.

The numeral 1 in the drawings indicates the main frame of a locomotive, 2 is the

trailing truck connected at its forward end 55 to the main frame 1 and provided at its rear end with draft rigging 3. This arrangement of the parts provides for the transmission of all pulling and buffing stresses through the trailing truck, rather 60 than through the rearward portion of the locomotive above the trailing truck. Roller or rocker bearings 4 are mounted on the top surface of the trailing truck to support the rear end of the locomotive. 65

Mud ring 5 which is located over the upper edges of the ash pan 6 is provided on its forward end with depending feet 7. These feet 7 are preferably formed integrally with the mud ring and are adapted to slide longitudinally in a groove in the main frame 1 but held against lateral displacement. Along the lower rear edge of mud ring 5 and projecting rearwardly therefrom, the deck plate 8 is formed as an integral portion of the mud ring construction. Deck plate 8 comprises side and end members of channel shape cross section and has longitudinal ties 9 of I-shaped cross section. Centrally located on the rear member of the 30 deck plate 8, a bracket 10 is provided for the support of the cab sheet, not shown.

Integrally formed brackets 11 adapted to bear on rocker supports 4 are located underneath and at the side adjacent the point of 85 merging between deck plate and mud ring portions of the frame. Suitable webbing 12 is provided to support the portion of these brackets which extend beyond the main body of the deck plate 8. 90

As shown in the preferred form which is illustrated in Figures 1 and 2, provision is made for an automatic stoker, not shown, by providing brackets 13 on the forward portion of the upper surface of the longitudinal 95 ties 9. However, all types of stokers cannot be accommodated by support in this location, so in the modified form illustrated in Figures 3 and 4, integrally depending lugs 14 are provided on the forward member 100 of the deck plate 8. Lugs 14 are provided with brackets 15 which suitably fit types of stokers other than those accommodated by the brackets 13 shown in Figures 1 and 2. Bracket 16 depends from the rear member 105 of deck plate 8 to form a supporting member for the rear cab sheet in this construction.

The lower edges of the inner and outer fire box sheets terminate at the mud ring 5. These sheets are suitably fastened to the mud ring preferably by rivets. Figures 5 to 10 inclusive illustrate cross sectional views of various styles of mud rings and the method of fastening the fire box sheets to this member. The mud ring 5 in Figure 5 is solid and substantially rectangular in cross section. The inner fire box sheet 17 and the outer fire box sheet 18 are fastened by a single rivet passing through both sheets and the mud ring.

In the form shown in Figure 6 the mud ring 19 is of inverted U-shaped cross section and separate rivets are used for fastening the inner and outer fire box sheets 17 and 18, respectively.

The modification shown in Figure 7 is similar to that of Figure 6 except that the sides of the mud ring 20 are inclined to the vertical and inwardly extending beads 21 are provided along the lower edges. In this form the fire box sheets have their lower edges slightly bent to conform to the mud ring and separate rivets are used for each sheet.

In Figure 8 a hollow mud ring 22 is shown. Shoulders 23 incline to the vertical and are provided for contact with the fire box sheets. Openings 24 in the lower surface permit access to the interior for the purpose of riveting the fire box sheets in place. Inwardly extending beads 25 surround the openings 24.

Figure 9 illustrates a mud ring 26 similar to the one shown in Figure 8, the difference being that the ring is shallower and the beads surrounding the openings are omitted. In this mud ring the sides throughout their length are inclined to the vertical instead of having vertical sides with an inclined shoulder as shown in Figure 8.

The tubular mud ring 27 shown in Figures 3, 4 and 10 is for use with a water tube boiler. With this type of boiler a single fire box sheet is carried by lugs 28. Water tubes 29 connect with the mud ring 27 so that the water circulates through the mud ring as well as through the tubing. Lugs 30 are provided on the inner side of mud ring 27 to carry the grate bars, not shown. The upper ash pan portion 31 is formed integrally with mud ring 27 and joined thereto by members 32. The ash pan 33 is carried by the upper ash pan portion.

It can be readily understood that the unitary construction of the mud ring and deck plate and their component parts as set forth herein forms a stronger construction than the same weight of metal in a fabricated structure and a lighter structure for the necessary strength than is possible with the fabricated construction. There are no joints to work loose and there is no main-

tenance after the member is once assembled into a locomotive.

It is to be understood that minor changes in the size, form and construction of the various parts of my device may be made and substituted for those herein shown and described without departing from the spirit of my invention as expressed in the following claims.

I claim:

1. As a new article of manufacture, a locomotive mud ring having a deck plate formed therewith.
2. As a new article of manufacture, a locomotive mud ring having a deck plate formed therewith, and means formed with said deck plate for the attachment of a stoker.
3. As a new article of manufacture, a locomotive mud ring having a deck plate formed therewith, and integrally formed bracket for the attachment of a stoker.
4. As a new article of manufacture, a locomotive mud ring having a deck plate formed therewith, and a bracket on said deck plate for the attachment and support of the rear cab sheet.
5. As a new article of manufacture, a locomotive mud ring having a deck plate formed therewith, and means on said mud ring for attachment of a fire-box sheet.
6. As a new article of manufacture, a locomotive mud ring having a deck plate formed therewith, and an integrally formed bracket on the underside of said member adapted to bear on the rocker support of a trailing truck and support said member.
7. As a new article of manufacture, a locomotive mud ring having a deck plate formed therewith, and an integrally formed foot at the forward end of said mud ring, said foot being adapted to be in contact with the main frame of the locomotive to form a connection and support for said mud ring.
8. In a locomotive having a main frame and a trailing frame connected thereto, said trailing frame being provided with draft mechanism and adapted to transmit the pulling and buffing stresses, a mud ring connected to said main frame and extending over said trailing frame, and a deck plate formed integrally with said mud ring.
9. In a locomotive having a main frame, a mud ring supported by said main frame and extending rearwardly therefrom, a deck plate formed integrally with said mud ring, a bracket on said deck plate portion for the support of the rear cab sheet, brackets for the support of a stoker, and means on said mud ring for the attachment of a fire-box sheet.
10. In a locomotive having a main frame, a mud ring supported by and extending rearwardly from said main frame, a deck plate formed integrally with said mud ring, said deck plate including side pieces, an end

piece, and a longitudinally disposed sill between said side pieces, and a bracket formed on said longitudinally disposed sill of said deck plate portion adapted for the connection and support of a stoker.

11. In combination with a locomotive having a main frame, a mud ring having an integrally formed depending foot at its forward end, said foot being adapted for the support of said mud ring by the rearward portion of said main frame.

12. In a locomotive having a main frame, a mud ring supported by and extending rearwardly from said frame, and a portion of the ash pan formed integrally with said mud ring.

13. In a locomotive having a main frame, a mud ring supported by and extending rearwardly from said main frame, and grate bar supporting lugs formed integrally with said mud ring.

14. In a locomotive having a main frame, a mud ring supported by and extending rearwardly from said frame, and formed with said mud ring as integral parts, fire box sheet supporting lugs, grate bar carrying lugs, and the upper ash pan portion.

In testimony whereof I hereunto affix my signature this 7th day of December, 1926.

WILLIAM M. SHEEHAN.
